22 Claims. (Cl. 93—93)

1

This invention relates to delivery mechanism for use with printing and like machines, for example newspaper printing machines, in which sheet products are deposited in regular succession, for delivery by a conveyor, and has for its general object the provision of a novel and improved mechanism for the delivery of regular, counted batches of the products from the machine.

The more detailed objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrates two embodiments of the invention, and, together with the description, serve to explain the principles of the invention.

In the drawings:

Figure 1 is a side elevation of a batching mechanism in accordance with the invention in association with product-depositing means of the rotary fly type;

Figure 2 is a plan view of the conveyors and their mountings illustrated in Figure 1;

Figure 3 is a diagrammatic detail view showing the parts of the batching mechanism illustrated in Figure 1, in the positions they occupy immediately preceding the segregation of a batch;

Figures 4, 5 and 6 are views similar to Figure 3, but showing further stages in the segregation and deposition of a batch;

Figure 7 is a diagrammatic elevational view illustrating a general arrangement of the delivery mechanism in accordance with the invention, in association with a bundling device of the kind already referred to;

Figure 8 is a diagrammatic view of the depositing means and part of the delivery conveyor, similar to the corresponding part of Figure 7, but illustrating a modified form of gearing between the depositing means and delivery conveyor;

Figure 9 is a sectional plan view of a mechanical synchronising device for gearing the product depositing means to the delivery means and to a bundling device used in association therewith to receive the batches therefrom;

2

Figure 10 is a fragmentary side elevation of the mechanism illustrated in Figure 9;

Figure 11 is a diagrammatic view illustrating an electrical system of synchronising the product depositing means and a bundling device, which may be used as an alternative to the mechanical arrangement illustrated in Figure 9.

The invention is particularly intended for application to delivery mechanism embodying a depositing means of the rotary fly type comprising a rotary member carrying the sheet products at its periphery, from which they are stripped by fixed or movable stops so as to be deposited on a conveyor. The invention may also be used in association with a bundling device comprising a plurality of receivers which are successively presented to receive the products from a delivery conveyor and remove them in separate bundles.

With newspaper delivery mechanism hitherto in use, difficulty has been experienced in operation due to variation in the number of products in successive batches, this difficulty arising primarily from the fact that the products are discharged from the conveyor in a continuous stream in regular and relatively close overlapping relationship, and are segregated into bundles by separator elements which are interposed between the last and first copies of consecutive groups. Since the interval between the leading edges of successive copies is small, it will be appreciated that it is difficult to ensure accurate selection of the copies to be separated.

With a view to avoiding this difficulty, the present invention provides a delivery mechanism for use with printing and like machines in which sheet products are deposited in regular succession, for delivery by a conveyor, comprising means operative at the stage at which the products are deposited, for producing greater spacing on the conveyor of successive series of products than of individual products in a series.

Such increased spacing of successive series of products on the conveyor may be effected by temporarily interrupting their deposition on the conveyor after deposition thereon of a batch of predetermined number and, in further accordance with the invention, the interrupted means may be combined with means for accelerating the removal of said batch from the depositing position.

According still further to the invention, the delivery mechanism comprises means operable upon deposition on said conveyor of a batch of products of predetermined number, for removing said batch from the depositing position on

the conveyor at a speed greater than that of said conveyor, and means for preventing subsequent products from being deposited on said conveyor until the removal of said batch, has been completed.

In carrying the invention into effect, the products may be periodically removed from the conveyor on which they are deposited, by means of a second conveyor which is driven at a speed greater than that of the first conveyor. Conveniently, said second conveyor is mounted so that it can occupy positions in or out of the path of the products after deposition, and is controlled by means operating in timed relation with the depositing means so as to become operative for the removal of the products upon the deposition of a predetermined number thereof.

The means for interrupting the deposition of the products after deposition of a predetermined number thereof may comprise one or more retaining elements carried by a rotary member driven in timed relation with the depositing means, said member and the element or elements thereon being arranged so that in the course of rotation of the member, the element or elements move through a zone in which the products are deposited thereon and are supported thereby. Such retaining element or elements may be pivotally mounted on the rotary carrying member and be arranged to rock, during rotation of said member, so that the entry to and departure from the product-retaining zone of the or each element is accelerated relative to the rotary member, for the purpose, respectively, of assisting accurate selection at high speeds of the proper product to be retained, and avoiding interference with the completed batch of products when it is being rapidly removed. The rocking movement is also controlled in the intervening period to maintain the retaining element or elements in a desired retaining attitude relative to the conveyor in order to avoid interference with the conveyor and with the products in the preceding batch.

If the delivery mechanism is used in association with a bundling device of the kind already referred to, a drive must be provided for operating the bundling device in constant phase relationship with the delivery mechanism so that its receivers may maintain a set registry with the delivery of the batches of products segregated by the delivery mechanism; moreover, in order to permit of disposal of batches left on the conveyor when the depositing means stop, the bundling device must be able to operate independently of the depositing means; and in this connection according to a further feature of the invention, means are provided for automatically bringing the bundling device into predetermined phase relation with the depositing means when normal running commences.

It is to be understood that the foregoing general description and the following detailed description are exemplary and explanatory of the invention but are not restrictive thereof.

Referring now to the examples of construction illustrated in the accompanying drawings, and considering first the batching mechanism illustrated in Figures 1 to 8, it will be seen that depositing means is provided by a rotary fly 10 of the well known type having a plurality of pockets formed by vanes 11 secured to and extending from the periphery of one or more rotatable drums 12. Preferably those portions of the vanes 11 which co-operate with the drum to

form the pockets are concentric with respect to the axis of the drum. Stationary or movable stops (not shown) of any known or desired kind are provided beneath the fly to strip the products

5 from the fly pockets and cause them to drop successively and in overlapping relationship on to a conveyor moving relatively slowly as compared with the fly. This conveyor consists of a plurality of laterally spaced endless conveyor bands 13, 10 passing at the entry end of the conveyor around drums 14 mounted on a shaft 15 rotatable about a fixed axis, and at the discharge end about drums 16 which are mounted by arms 17 on a rockable shaft 18 so as to be movable in a vertical plane, and is of such length as adequately 15 to accommodate on its upper run a batch of products of predetermined number, for example, a quire of twenty-seven.

Also arranged beneath the fly 10 and extending 20 beyond the discharge end of the aforesaid conveyor 13 is a second conveyor similarly comprising a plurality of laterally spaced conveyor bands 19 which are interposed, transversely of the mechanism, between the bands of the conveyor 13. The bands 19 at the entry of the conveyor, pass around drums 20 carried by arms 21 on a rockable shaft 22 so as to be capable of movement in a vertical plane, whilst at the discharge end they are mounted on drums 23 carried by a shaft 24, which is rotatable about a fixed axis and also carries drums 25 around which pass bands constituting the first section of the main conveyor 26 (see Figure 7) leading to the ultimate discharge point. The shafts 15 and 24 25 are interconnected by chain and sprocket gearing 27 so that the speed of the conveyor 19 is greater than that of the conveyor 13. The two conveyors are, furthermore, driven in timed relation with the rotary fly 10 by means described 30 hereinafter.

The object of the vertical movement of the drums 16 and 20 is to permit raising and lowering of the two conveyors 13 and 19 to bring either of them, as desired, into and out of a position

45 for engagement with the deposited products, and to assist in achieving this object the arms 17, 21 have extensions 28, 29 respectively, beyond their axes of rotation, these extensions carrying further drums 30, 31 which co-operate respectively with the conveyor bands 19, 13. The rock shafts 18, 22 are interconnected by a link 32 secured to arms 33 on the shafts so as to move in unison, and the setting is such that when (as shown in Figure 1) the drums 20 and 30 are lowered, to bring the faster conveyor 19 out of the operative position, the drums 16 and 31 are moved to raise the slower conveyor 13 into a product-receiving position. Conversely, (as shown in Figure 4) when the drums 20, 30 are 50 moved to raise the conveyor 19, the drums 16, 31 are lowered.

The two sets of arms are operated in timed relationship with the rotary fly 10 by means of a rotary cam 35, acting through a spring-tensioned 55 follower arm 36 pivoted at 37 and connected by a link 38 to an arm 39 secured to the rock shaft 18. In the case illustrated in Figure 1, the cam 35 is geared (the gearing not being shown) to rotate one revolution during the deposition by the fly of two batches (e. g. quires) of products, and is therefore designed to provide two complete cycles of the conveyor raising and lowering movement for each revolution. During each cycle, the conveyor 13 is maintained in the raised or operative position for a period sufficient to allow the

deposition thereon of one complete batch; immediately thereafter, the conveyor 13 is quickly lowered and the conveyor 19 quickly raised to enable the latter to effect the removal of the batch at an increased speed. In the position shown in Figure 1, the latter part of the cycle is about to take place.

When a batch of products of the required number has been deposited by the fly 10 on the slower conveyor 13 and has been raised from said conveyor by the faster conveyor 19 for removal to the conveyor 26, it is essential that products subsequently delivered by the fly be prevented from dropping on to the faster conveyor 19 until the latter conveyor, having removed the batch to a desired distance from the fly, which may approximate to the distance occupied by a complete batch, resumes its lowermost position and the slower conveyor 13, having then been raised, is in position to receive further products from the fly 10. For this purpose retaining members 40 are provided which are formed with stop portions 41 for stripping the subsequent products successively from the fly, and also with fingers 42 which, on completion of a batch, are movable from an inoperative position to a product-retaining position immediately beneath the fly, there to receive the products stripped from the fly by said stop portions 41. These fingers are pivotally mounted at 43 on a rotary member 44 mounted on the same shaft as, and thus rotating with, the cam 35, the timing of the rotation being such that as the last product in a batch is deposited by the fly on to the slower conveyor 13, a retaining member 40 reaches a position in which, by rocking it about its pivot 43, the finger portion 42 thereof may be brought to a product-retaining position beneath the fly, the stops 41 at the same time becoming operative to strip the following products, which fall upon the fingers 42. This rocking movement is effected by the engagement of a follower roller 45, carried by the retaining members 40, with a stationary cam plate 46, the members 40 being biased by springs 47 to maintain constant engagement of the follower roller 45 with the cam plate 46.

Since the member 44 carrying the retaining members 40 rotates, like the cam 35, one revolution during the deposition by the fly of two batches of products, two retaining members 40, or sets thereof, are provided at diametrically opposite position on the rotary member 44.

The sequence of movements of each retaining member 40 from a position immediately preceding its entry to the product-retaining zone to its position of departure therefrom, is illustrated in Figures 1, 3, 4, 5 and 6. As can be seen therefrom, the cam 46 is so designed that as a retaining member 22 approaches a position adjacent the lower part of the fly 10, the fingers 42 are maintained until the last moment above the fly pockets (see Figure 3) so as not to intercept the products being delivered by the fly, which at this period are being stripped from the fly by the normal stripping means (not shown). Immediately the deposition of a batch of products on the slower conveyor 13 has been completed the member 40 is rocked by a rise of the cam 46 to accelerate the downward movement of the fingers 42 to a position of support for following products (see Figure 1), which are now stripped from the fly by the stops 41. This movement of the fingers 42 is slightly in advance of the raising of the faster conveyor 19 to lift the batch from the slower conveyor 13.

Notwithstanding the continued rotation of the carrying member 44, the fingers 40 are kept clear of the conveyor 13 and the rearmost product of the previous batch, and are also constrained to maintain a convenient product-retaining attitude, by rocking rearwardly relative to the member 44, under the influence of the cam 46 (see Figures 4 and 5). As the movement progresses, the two conveyors 13, 19 are gradually resuming their original positions i. e. the faster conveyor 19 is being lowered and the slower conveyor 13 raised as the completed batch moves progressively further from the fly, and the plane of intersection of said conveyors moves in the same direction. The relative speeds of the various elements are so selected that the free ends of the fingers 42 lag to some extent behind this advancing plane of intersection, although, during the concluding phase of the conveyor adjustment, they are still advancing at a speed greater than that of the slower conveyor 13 and the products carried by said fingers are thus gradually transferred to said slower conveyor. When the faster conveyor 19 has moved the preceding batch of products out of the way of the products supported by the fingers 42, the retaining member 40 is constrained by a rise on the cam 46 to rock forwardly (see Figure 6) so that the fingers 42 are moved rapidly from the product-retaining zone, the fly thereafter delivering products in succession to said conveyor 13 in the usual manner until another batch is completed, whereupon the second retaining member comes into operation to interrupt the deposition on the conveyor 13 of further products.

From the foregoing it will be clear that as a completed batch of products will be rapidly moved from a position adjacent the fly 10, a substantial spacing is provided between successive batches without in any way affecting the speed continuity of operation of the fly. This precludes products in one batch becoming mixed with another batch and thus ensures that all batches contain the desired number of products.

As compared with a delivery system in which the products are segregated into batches by interposing separator elements between successive products being delivered by a conveyor in closely overlapping relationship, accuracy of selection is more readily obtainable by reason of the greater interval between the products on the fly. Another advantage which derives from this arrangement is that, where the products are discharged into a bundling device of the kind already referred to, the conveyor wires leading from the fly to the bundling device need not move with such exact and regular speed as has hitherto been essential. A still further advantage is that the last one or two products may easily be removed from a batch and replaced by substitutes without any error occurring in the number of products in the batch.

When the delivery mechanism described in the foregoing is used in association with a bundling device of the kind referred to, it is important that the bundler should, within reasonably close limits, be in proper phase relationship with the depositing means and delivery mechanism to ensure that the batches of products are accurately placed in the receivers, and to this end the bundle 59 (see Figure 7), when in normal operation, is driven through chain gearing 80, spur gearing 81, and chain gearing 82 from the delivery conveyor 26, which in turn is coupled to the rotary fly through a gearbox 83 and chain gearing 84, 52 and 75 sprocket 53. In the case illustrated in Figure 7,

the sprocket 53 is on a shaft 51 which carries the fly and from which a shaft 72 (which carries the rotary member 44 and cam 35) is driven by separate gearing (not shown). In Figure 8, the sprocket 53' is coaxial with, but rotatable independently of the cam shaft 72, and is driven by spur gears 85, 86, of which the latter is driven by a spur gear 87 on the fly shaft 51, and also drives a spur gear 88 on the cam shaft 72 through an intermediate 89. In this arrangement, by making the gear 86 of the composite type, embodying two or three gear wheels having slightly differing numbers of teeth, and by making the wheel 87 slidably on its shaft 51, provision may be made for varying the transmission ratio both to the cam shaft 72 and bundles 50 to suit different numbers of products in a batch. In either Figure 7 or Figure 8, the rate of operation of the bundle 50 and conveyor 26 will be directly related to that of the fly.

At the same time, provision must be made for discharging any batches left on the delivery conveyor when the press stops, and means; for example, an independent electric motor on the bundler, and a suitable clutch connection between the depositing means and the conveyor 26 are therefore provided for enabling the bundler 50 and discharge conveyor 26 to be driven independently of the fly. To allow independent operation of the bundler and conveyor, and yet provide that they shall be brought automatically into proper phase relationship with the fly on re-starting the latter, a synchronising device is employed, alternative forms of which are illustrated in Figures 9 and 10 and Figure 11.

In the mechanism illustrated in Figures 9 and 10 the sprocket 53 of the chain gearing 52 is mounted free on the fly shaft 51 and receives its drive therefrom through a free-wheel or ratchet clutch, of which the driving member is a ring 54 formed with ratchet-type dogs 55 engaging corresponding dogs on the end face of a double pinion 56 fixed on the sprocket 53. The ring 54 is mounted so as to be capable of axial movement, against the action of springs 57, in the recessed end of an eight-toothed ratchet wheel 58, with which it has a driving connection through splines 59, the ratchet wheel 58 having an axial extension 60 by which it is mounted fast on the fly shaft 51. It will be apparent that, by this arrangement, whilst the drive of the fly shaft may be transmitted to the bundler, the latter may overrun the fly shaft so that it may be driven independently of and at a higher speed than said shaft, for example by the means provided for driving the bundler and conveyor when the machine has stopped. After being so driven, the bundler may be out of phase with the fly, and to enable this to be corrected on re-starting an alternative drive from the fly shaft 51 to the sprocket 53 is provided by way of a speed-increasing gear train comprising a phase-adjusting gear 61 free on the extension 60 of the ratchet wheel 58; gears 62, 63 on a countershaft 64; and pinion 65 of the double pinion 56 associated with the sprocket 53. This alternative drive is transmitted from the ratchet wheel 58 to the phase-adjusting gear 61 by means of a spring-pressed pawl 66, pivoted on the gear 61, the engagement of the said pawl with the ratchet wheel 58 being controlled by a timing element formed by a sleeve 67 free on the hub of the phase-adjusting gear 61. Said timing element is provided with a projection 68 which is adapted to co-operate with a lateral extension 69 of the pawl 66 to raise it out of engagement with

the ratchet wheel 58, and the element is further provided with a chain sprocket 70 which is continuously driven from a sprocket 71 on the shaft 72.

As has already been stated, the shaft 72 is driven (by means not shown) at the rate of one revolution for two batches of products deposited by the fly 10. The speed ratio of the sprockets 71, 70 in the example illustrated is 2:1, so that the sprocket 70 makes one revolution per batch. Similarly the speed ratio of the gear train from the pinion 65 to the phase-adjusting gear 61 is such that the latter is rotated at the rate of one revolution per batch when the drive from the fly shaft 51 to the bundler is being transmitted normally through the clutch 54, under which condition the pinion 65 rotates at the same speed as the fly shaft 51, and of course, drives the phase-adjusting gear 61 through the countershaft gears 63, 62. It will be apparent that, so long as the projection 68 on the timing element 67 is in register with the part 69 of the pawl 66 on the phase-adjusting gear 61, the drive to the bundler will be transmitted normally: if, however, the part 69 moves out of register with the projection (see Figure 10), the pawl is allowed to engage the ratchet wheel 58 and, since the latter is rotating with the fly shaft 51, a drive is transmitted through the pawl 66 to the phase-adjusting gear 61 and thence to the gears 62, 63, 65. Since the gear train in this direction provides a speed-increasing ratio, the pinion 65 and sprocket 53, and therefore the bundler are driven at an increased speed relative to the fly, the ratchet clutch 54 permitting overrunning. Under these conditions, the phase-adjusting gear 61 is rotating faster than the timing element 67, so that after a time the pawl 66 again registers with the projection 68, whereupon the alternative drive is disconnected and the normal drive resumed.

Conveniently, as applied to a newspaper printing press, the number of teeth in the gears 65, 63, 62, 61 are, respectively twenty-seven, fifty-four, sixteen and fifty-two, a ratio which corresponds to a quire of twenty-six copies if the rotary fly deposits four copies per revolution. As, however, it frequently happens that the same press is required to deliver quires of twenty-seven copies, provision is made for varying the gear ratio. For this purpose, the second part 75 of the double pinion 56 has twenty-six teeth, and a removable spacing collar 76 is provided on the countershaft 64, upon removal of which the gears 62, 63 may be adjusted along the countershaft to mesh the gear 63 with the pinion 75 instead of the pinion 65.

It will be appreciated that when the number of copies in a quire is changed, it is necessary to modify the speed of the shaft 64 relative to that of the fly shaft 51. The change of ratio of the gears 65, 63, 62, 61 enables the speed of the phase-adjusting gear 61 to be kept equal to that of the timing element 67 at one revolution per two quires.

In the alternative synchronising device illustrated in Figure 11, lack of synchronism between the bundler and the depositing means is caused to unbalance a Wheatstone bridge circuit, and the resultant current flowing in the diagonal arm of the bridge is utilised to close the circuit of a motor driving the bundler, the motor being again stopped when synchronism is achieved and there is no current flow in the diagonal of the bridge. In Figure 11, 90 is the supply to a Wheatstone bridge having fixed re-

sistance arms 91, 92, variable resistance arms 93, 94, and diagonal arm 95. The variable resistance arms 93, 94 are composed each of an identical set of independent resistance of graded value, each resistance being connected to a separate contact of a corresponding circular switch 96, 97. One of these switches, say 96 is geared to the depositing means, for example to the cam shaft 72, and the other 97, to the bundler through sprockets 106, 107, so that when the speeds of the bundler and cam shaft are correctly related the two switches rotate at equal speed. The switches 96, 97 are also set so that when the bundler and cam shaft are in proper phase relation the resistances 93, 94 brought into the Wheatstone bridge circuit by the switches 96, 97 at any instant are of equal value, and accordingly that there is no current flow in the diagonal arm 95. It will be apparent that, in these circumstances, if the bundler and cam shaft 72 are out of phase, the switches 96, 97, will also be out of phase and that at any instant resistances 93, 94, of different value will be brought into circuit. The current flow thus produced in the diagonal arm 95 is utilised to energise a relay 98 which closes a switch 99 in the supply circuit of a motor 100, which is adapted to drive the bundler through a worm gear 101, one-way ratchet clutch 102, and shaft 103, the object of the ratchet clutch 102 being to allow the bundler to be driven in normal operation without driving the motor 100. The synchronising system is not intended to operate during normal use of the bundler, but only after the bundler has been operated independently of the depositing means, and in order to prevent operation of the synchronising device except at that time, the supply 90 to the bridge circuit includes contacts 104 which are controlled by a contact 105 associated with the main starting gear of the machine and which is arranged to complete the bridge supply circuit 90 only when the machine has been stopped. This electrical synchronizing system differs from the mechanical system hereinbefore described in that, while the latter, due to the power supply being cut off when the press is stationary, operates immediately before commencement of a new run, the electrical system becomes operative immediately the press has been shut down.

What we claim and desire to secure by Letters Patent of the United States is:

1. A delivery mechanism for use with printing and like machines handling sheet products, including in combination conveyor delivery means, means for depositing sheet products in regular succession, for delivery by the conveyor delivery means, and rotatably driven means for engaging under and supporting portions of the products above said conveyor means at spaced intervals of time, for producing greater spacing on the conveyor delivery means of successive series of products than of individual products in a series.

2. A delivery mechanism for use with printing and like machines handling sheet products, including in combination conveyor delivery means, means for depositing sheet products in regular succession, for delivery by the conveyor delivery means, and rotatably driven means for engaging under and supporting portions of the products above said conveyor means at spaced intervals of time, for producing complete separation along the conveyor delivery means of successive series of products whilst retaining an overlapping relationship between individual products in a series.

3. A delivery mechanism for use with printing and like machines handling sheet products, including in combination conveyor delivery means, means for depositing sheet products in regular succession, for delivery by the conveyor delivery means, means operative upon deposition on said conveyor delivery means of a batch of products of predetermined number, for accelerating the removal of said batch from the depositing position, and rotatably driven means for engaging under and supporting portions of the products above said conveyor means acting simultaneously with said accelerating means to interrupt temporarily the deposition of subsequent products on said conveyor delivery means.

4. A delivery mechanism for use with printing and like machines handling sheet products, including in combination conveyor delivery means, means for depositing sheet products in regular succession, for delivery by the conveyor delivery means, and rotatably driven means for engaging under and supporting portions of the products above said conveyor means operable upon deposition on said conveyor delivery means of a batch of products of predetermined number, for interrupting temporarily the deposition of subsequent products on said conveyor means.

5. A delivery mechanism for use with printing and like machines handling sheet products, including in combination conveyor delivery means, means for depositing sheet products in regular succession for delivery by the conveyor delivery means, means, operable upon deposition on said conveyor delivery means of a batch of products of predetermined number, for removing said batch from its position of deposition on the conveyor delivery means at a speed greater than that of said conveyor means, and rotatably driven means for engaging under and supporting portions of the products above said conveyor means for preventing subsequent products from being completely deposited on said conveyor delivery means until the removal of said batch has been completed.

6. A delivery mechanism for use with printing and like machines handling sheet products, including in combination means for depositing sheet products in regular succession, a first conveyor on which the products are deposited, a second conveyor driven at a speed greater than and arranged in longitudinally overlapping relation with said first conveyor, mounting means for said conveyors including pivoted arms enabling each conveyor to be adjusted to and from a product-engaging position, interconnecting means between said arms whereby the conveyors are adjustable simultaneously but in opposite senses, and means, operating in timed relationship with the depositing means, for actuating said arms to effect the conveyor adjustment.

7. A delivery mechanism for use with printing and like machines handling sheet products, including in combination means for depositing sheet products in regular succession, a first conveyor on which the products are deposited, a second conveyor arranged in longitudinally overlapping relationship with respect to said first conveyor and driven at a speed greater than that of said first conveyor, means for adjusting said second conveyor to periodically remove products from said first conveyor, and means, operative when said second conveyor is adjusted for such removal, for interrupting temporarily the deposition of further products on said first conveyor.

8. A delivery mechanism for use with printing and like machines handling sheet products, including in combination conveyor delivery means, means for depositing sheet products in regular succession, for delivery by the conveyor delivery means, and means, operable upon deposition on said conveyor delivery means of a batch of products of predetermined number, for interrupting temporarily the deposition of subsequent products on said conveyor means, said interrupting means comprising a rotary member driven in timed relation with the depositing means and at least one product-retaining element carried by said member, and the member being arranged so that in the course of its rotation said retaining element moves through a zone in which products are deposited and supported thereon.

9. A delivery mechanism for use with printing and like machines handling sheet products, including in combination conveyor delivery means, means for depositing sheet products in regular succession, for delivery by the conveyor delivery means, and means, operable upon deposition on said conveyor delivery means of a batch of products of predetermined number, for interrupting temporarily the deposition of subsequent products on said conveyor means, said interrupting means comprising a rotary member driven in timed relation with the depositing means and at least one product-retaining element pivotally mounted thereon, the member being arranged so that in the course of its rotation said retaining element moves through a zone in which products are deposited and supported thereon; and means for rocking said retaining element about its pivot so that its entry to and departure from the product-retaining zone is accelerated relative to the rotary member, and its position relative to the rotary member is modified to maintain a desired retaining attitude in passing through said zone.

10. A delivery mechanism for use with printing and like machines handling sheet products, including in combination conveyor delivery means, means for depositing sheet products in regular succession, for delivery by the conveyor delivery means, and means, operable upon deposition on said conveyor delivery means of a batch of products of predetermined number, for interrupting temporarily the deposition of subsequent products on said conveyor means, said interrupting means comprising a rotary member driven in timed relation with the depositing means and at least one product-retaining element pivoted on and extending outwardly from said member, the member being arranged so that in the course of its rotation said retaining element moves through a zone in which products are deposited and supported thereon; and means for rocking said retaining element to vary its angular position relative to the member at different stages in the product-retaining zone, said rocking means being timed so that, by reason of the rocking movement, entry of the retaining element to and its departure from the product-retaining zone is accelerated relative to the rotary member.

11. A delivery mechanism for use with printing and like machines handling sheet products, including in combination conveyor delivery means, depositing means of the rotary fly type having a rotatable element with vanes to receive sheet products and deposit them in regular succession for delivery by the conveyor delivery means, a rotary member parallel and driven in timed re-

lation with the rotatable element, and at least one product-retaining element carried thereby, said member being arranged so that in the course of its rotation any retaining element thereon moves through a zone in which products from the vanes are deposited and supported thereon.

5 12. A delivery mechanism for use with printing and like machines handling sheet products, including in combination conveyor delivery means, depositing means of the rotary fly type having a rotatable element with vanes to receive sheet products and deposit them in regular succession for delivery by the conveyor delivery means; a rotary member parallel and driven in timed relation with the rotatable element; and at least one product-retaining element pivoted on and extending outwardly from said member, the member being arranged so that in the course of its rotation said retaining element moves through a zone in which products are deposited thereon from said vanes and supported thereon; and means for rocking said retaining element to vary its angular position relative to the member at different stages in the product-retaining zone, said rocking means being timed so that, by reason of the rocking movement, entry of the retaining element to and its departure from the product-retaining zone is accelerated relative to the rotary member.

20 13. A delivery mechanism as claimed in claim 12, having the further feature that the retaining element includes a stop portion acting to strip a product from the vanes of the rotatable element upon entry into the product-retaining zone.

25 14. A delivery mechanism for use with printing and like machines handling sheet products, including in combination depositing means of the rotary fly type having a rotatable element with vanes to receive sheet products and deposit them in regular succession; a rotary member parallel and driven in timed relation with the rotatable element and having at least one product-retaining element thereon, said member being arranged so that in the course of its rotation said retaining element moves through a zone in which products are deposited thereon from said vanes and supported thereon whereby normal deposition of products is interrupted; a first conveyor positioned to receive products deposited by the rotatable element; a second conveyor driven at a speed greater than that of said first conveyor; means for adjusting said second conveyor to periodically remove products from said first conveyor; and means for timing such adjustment to take place during the period of interruption by said retaining element of normal deposition.

30 15. A delivery mechanism for use with printing and like machines handling sheet products and adapted to deliver to a bundling device having a plurality of receivers which are successively presented to receive the products and remove them in separate bundles, including in combination conveyor delivery means; means for depositing sheet products in regular succession, for delivery by the conveyor delivery means; means, operative at the stage at which said products are deposited, for producing greater spacing on the conveyor delivery means of successive series of products than of individual products in a series; means for driving a bundling device in constant phase relationship with the delivery mechanism so that the receivers of said device may maintain a set registry with the delivery of batches segre-

gated by said spacing means; means for enabling a bundling device to operate independently of the depositing and spacing means so that the conveyor means may be emptied when the depositing means have stopped; and means for automatically bringing a bundling device into predetermined phase relation with the depositing means after independent operation.

16. A delivery mechanism for use with printing and like machines handling sheet products and adapted to deliver to a bundling device having a plurality of receivers which are successively presented to receive the products and remove them in separate bundles, including in combination conveyor delivery means; means for depositing sheet products in regular succession, for delivery by the conveyor delivery means; means, operative at the stage at which said products are deposited, for producing greater spacing on the conveyor delivery means of successive series of products than of individual products in a series; means for driving a bundling device from the depositing means including a driving member and a driven member, a first driving connection adapted to drive the driven member in constant phase relationship with the driving member, a second driving connection adapted to drive said driven member at a changed speed to adjust its phase relationship with the driving member, means for rendering each of said connections ineffective whenever the other is operating, and means for rendering said second connection effective only when the phase relationship of said members is disturbed.

17. A delivery mechanism as claimed in claim 16, having the further features that the means for driving a bundling device from the depositing means includes a first driving connection formed by a one-way clutch adapted to drive the driven member in constant phase relationship with the driving member, and a second driving connection adapted, when in operation, to drive said driven member at an increased speed to cause it to overrun the one-way clutch and thus adjust the phase relationship of said members.

18. A delivery mechanism as claimed in claim 16, having the further feature that the means for driving a bundling device from the depositing means includes a second driving connection having a rotatable phase-adjusting element, a reversible transmission for driving said element from the driven member at a speed different from, but bearing a definite relation to that of said driven member, a clutch connection enabling said element to be driven by the driving member, and a timing element having means to render said clutch effective only when the phase-adjusting and timing elements are out of phase; said timing element being driven at a speed bearing a definite relationship to that of the driving member and normally equal to that of the phase-adjusting element so that if the phase-adjusting and timing elements, and therefore the driving and driven members, are out of a predetermined phase relationship, the phase-adjusting element is connected to the driving member to drive the driven member through the said reversible transmission with a change of speed.

19. A delivery mechanism for use with printing and like machines handling sheet products and adapted to deliver to a bundling device having a plurality of receivers which are successively presented to receive the products and remove them in separate bundles, including in combination conveyor delivery means; depositing means

of the rotary fly type having a rotatable element with vanes to receive sheet products and deposit them in regular succession for delivery by the conveyor delivery means; means, operative at the stage at which said products are deposited, for producing greater spacing on the conveyor delivery means of successive series of products than of individual products in a series, means for driving a bundling device from the depositing means including a driving member non-rotatably mounted on the shaft of said rotary carrier, and a driven member free on said shaft having an associated gear for transmission of the drive to a bundler; a first driving connection formed by a one-way clutch adapted to drive the driven member in constant phase relationship with the driving member; a second driving connection including a rotatable phase-adjusting element, a reversible transmission for driving said element from the driven member at a speed lower than, but bearing a definite relation to that of said driven member, a clutch connection enabling said element to be driven by the driving member, and a timing element having means to render said clutch effective only when the phase-adjusting and timing elements are out of phase; said timing element being driven at a speed bearing a definite relationship to that of the driving member and normally equal to that of the phase-adjusting element so that if the phase-adjusting and timing elements, and therefore the driving and driven members, are out of a predetermined phase relationship, the phase-adjusting element is connected to the driving member to drive the driven member through the said reversible transmission with an increased speed, the one-way clutch of the first driving connection permitting overrunning.

20. A delivery mechanism for use with printing and like machines handling sheet products, including in combination means for depositing sheet products in regular succession, a first conveyor on which the products are deposited at a particular position longitudinally of the conveyor for forwarding along said conveyor, a second conveyor driven at a speed greater than and arranged in longitudinally overlapping relation with said first conveyor adapted to remove products from said first conveyor at substantially said position where said products are deposited and forwardly thereof, mounting means for said second conveyor enabling it to be adjusted to and from a position in which it can remove from the first conveyor any products thereon at substantially said position where said products are deposited and forwardly thereof, and means operating in timed relationship with the depositing means for actuating said mounting means to adjust said second conveyor into a position for removal of products from said first conveyor.

21. A delivery mechanism for use with printing and like machines handling sheet products, including in combination means for depositing sheet products in regular succession, a first conveyor on which the products are deposited at a particular position longitudinally of the conveyor for forwarding along said conveyor, a second conveyor driven at a speed greater than and arranged in longitudinally overlapping relation with said first conveyor adapted to remove products from said first conveyor at substantially said position where said products are deposited and forwardly thereof, mounting means for said conveyor enabling each conveyor to be adjusted to

and from a product-engaging position to engage products at substantially said position where said products are deposited and forwardly thereof, and means operating in timed relationship with the depositing means for actuating said mounting means to adjust the conveyors alternately and simultaneously into and out of said product-engaging position.

22. A delivery mechanism for use with printing and like machines handling sheet products, including in combination means for depositing sheet products in regular succession, a first conveyor on which the products are deposited at a particular position longitudinally of the conveyor for forwarding along said conveyor, a second conveyor driven at a speed greater than and arranged in longitudinally overlapping relation with said first conveyor adapted to remove products from said first conveyor at substantially said position where said products are deposited and forwardly thereof, mounting means for said conveyors including pivoted arms enabling each con-

10
15

veyor to be adjusted to and from a product-engaging position to engage products at substantially said position where said products are deposited and forwardly thereof, and means operating in timed relationship with the depositing means for actuating said arms to adjust the conveyors alternately and simultaneously into and out of said product-engaging position.

WILLIAM ARNOLD WHITEHEAD.
